Filed May 8, 1963, Ser. No. 74,795

Term of patent 14 years

(Cl. D18—2)

FIG. 1

FIG. 2

FIG. 1 is a front face view of a ceiling tile or similar article showing the new design of our invention.

FIG. 2 is an edge view of the tile of FIG. 1 looking at the edge of the tile which is at the bottom in FIG. 1.

The dark grayish areas of the design and its modifications as shown in the drawing may be either eroded portions or may be printed and the irregularly shaped dots may be either holes punched into the tile or may be printed.

We claim:

The ornamental design for a ceiling tile or similar article, substantially as shown and as described.
